UNITED STATES PATENT OFFICE

2,616,352

RESILIENTLY MOUNTED DISK TILLER

Howard M. Johnston, Toronto, Ontario, Canada,
assignor to Massey-Harris Co. Ltd., Toronto,
Ontario, Canada, a corporation of Canada

Application August 15, 1947, Serial No. 768,867

1 Claim. (Cl. 97—53)

1

The present invention is adapted to be used as an attachment on disc tillers such as is illustrated in my application for patent, Serial Number 523,131, filed February 19, 1944, which matured into U. S. Patent No. 2,426,354 and issued August 26, 1947, entitled Disc Tiller. In this design the frame has considerable weight and the discs are held definitely to a certain depth relative to the frame. Therefore when tilling stony ground with a large stone near or at the surface of the ground, its contact with a disc or discs places a great strain on the mechanism because of the weight of the frame.

In the present invention, means are provided whereby the discs are yieldingly held at the predetermined operating depth so that they may pass over serious obstructions without injury to any part of the device.

An object of the present invention is to position the yielding means between the power lift and tube to which the discs are attached so the yielding means is operative at all times, and without adding very greatly to the cost of the device.

Objects of the present invention are to provide means whereby the yielding means may be made inoperative by the simple use of an additional bolt and whereby the yielding means may be manually adjusted.

To these and other useful ends my invention consists of parts, combinations of parts or their equivalents and mode of operation as herein-after described and claimed and shown in the accompanying drawings in which:

Fig. 1 is a top view of a disc tiller as shown in my United States Patent No. 2,426,354, and equipped with my stone jumping device.

Fig. 2 is a fractional left end view of the device shown in Figure 1.

Fig. 3 is an enlarged left side sectional view of the present invention in a normal operating position.

Fig. 4 is a view similar to Figure 3 except illustrating the action of the device when the discs are forced to ride over an obstruction.

Fig. 5 is a section taken on lines 5—5 of Figure 3.

Fig. 6 is a section taken on lines 6—6 of Figure 5.

Fig. 7 is an enlarged elevational view similar to Figure 5 of my United States Patent No. 2,426,354.

As thus illustrated the disc gang is designated by reference character A and the left end frame of the device is designated in its entirety by reference character B. The hitch of my device in its entirety is designated by reference character C.

Member A comprises a relatively large tube 10 having spaced arms 11 which are secured to the tube, the rear ends being suitably connected to disc gang bearings 12. Discs 13 are secured to a shaft which is rotatably mounted in bearings 12.

Tube 10 is rotatably mounted on a main frame

2

member or shaft 15, the shaft forming a rigid connection between member B and a bracket 16 to which a carrying and guiding wheel 17 is rotatably attached by means of an axle 18, the axle having secured thereto an arm 19. Hitch member C has a draw link 20 which is pivotally attached as at 21, its front being adapted to be attached to the draw bar of a tractor and having a link connection 22 to arm 19 whereby wheel 17 will be guided in its direction of travel by the tractor through link 20. The rear end of member B has a bracket 25 (see Figure 2) into which an axle 26 is vertically pivotally mounted, the axle at its rear end having rotatably mounted thereon a rear furrow carrying wheel 27.

Wheels 17 and 27 have means for vertical adjustment relative to bracket 16 and member B. The forward end of member B has rotatably mounted thereon a land wheel 28 with a power lift clutch 29 having a crank 30 with connections whereby the discs 13 may be raised and lowered to inoperating and operating positions by turning tube 10 on frame member 15, and having a forwardly extending shaft 31 whereby the operator from the seat on the tractor may regulate the depth cut by the disc as in United States Patent No. 2,426,354.

It will be seen that wheel 28 acts to definitely raise and lower the discs on gang A. If a serious obstruction is met, for example a large stone which is near the surface of the ground, in order to ride over the stone the disc gang will be required to lift either the front or rear end or both ends of the device, unless the machine is equipped with my present invention.

Applicant's structure as shown in the figures is designed so the lifting of the discs either by means of wheel 28 or shaft 31 is a comparatively simple matter and easily accomplished by simply turning tube 10 on shaft 15 as compared to a device wherein the discs are raised and lowered by raising and lowering the frame of the device.

It will be seen that in my disc tiller, absolute control over the depth of the disc is made possible and that the discs will be held substantially to a fixed depth in passing over hard or soft spots in the field. However, when the discs meet an unyielding obstruction such as a large stone near the surface of the ground, I provide means whereby the discs will be permitted to ride over the obstruction by overcoming springs supplied for the purpose and without raising the frame of the device.

I will now describe my stone jumping attachment or means whereby the discs are yieldingly held to the desired depth.

Referring specifically now to Figures 3, 4, 5, 6 and 7. In Figure 7, I have illustrated a mechanism for raising and lowering the discs and manually regulating the depth of the disc similar to that shown in said United States Patent No. 2,426,354. In Figures 1 through 6, I illustrate my improved means for yieldingly holding the

discs in the predetermined depth as determined by the power lift and manually operated controlling means.

Crank 30 is adapted to make a one half turn every time lever 32 is pulled. When the crank is in its upper position the discs will be in an operating position and when the crank is in its lowest position the discs will be in an inoperating position as follows:

Two split brackets 33—33 are rotatably mounted on tube 10, each have sectors 34—34 integral therewith. Two upwardly extending, parallel arms 35—35 are pivoted to sectors 34 as at 36. Sectors 34 each have a slot 37 which is positioned on a radius with bolt 36. Arms 35 have bolts 38 secured thereto which extend through slots 37 so members 33 may turn on bolts 36 as axes thus forming knuckle joints between members 33 and 35. A forwardly extending arm 45 is secured to pipe 10. A bracket 46 extends downwardly between arms 35 and having trunions 47 on opposite sides which extend through openings in arms 35. Member 46 has at its upper end a bevel gear housing 48, one of the bevel gears being operatively connected to shaft 31 and the other being screw threaded to a bolt 49 which is pivotally connected to arm 45 as at 50 and extends freely through bracket 46 to the bevel pinion into which it is screw threaded.

Thus by turning shaft 31 tube 10 may be turned on shaft 15 for manually controlling the operating position of the discs. Arms 35 are secured together at their upper ends by bracket 51 the bracket having a forwardly extending trunnion 52 which is operatively connected to crank 30 by means of blocks 53 and 54 and a forked connecting link 55 the forks being pivoted to the blocks as at 56 and 57. The upper end of link 55 is preferably screw threaded into the upper fork as at 58 as illustrated, for adjusting purposes and so crank 30 need not be parallel to tube 10.

Thus the position of arms 35 is determined by crank 30 and the position of arm 45 relative to arms 35 is determined by shaft 31. Clearly discs 13 are raised and lowered by the power lift and regulated manually by means of shaft 31.

Arms 65 and 66 are secured to members 33 having at their forward ends eye bolts 67. Brackets 68 are secured to the upper ends of arms 35 each having eye bolts 69 with nuts 70. Eyebolts 67 and 69 have therebetween pull springs 71, the springs acting to pull upwardly on the forward ends of members 65 and 66 and urge members 33 clockwise. Nuts 70 may be used for adjusting the tension of these springs, thus to regulate the yielding pressure adapted to hold the discs in the ground and to hold bolts 38 against the forward ends of slots 37.

It will be noted that the plane of pivot bolt 36 and trunnions 47 is slightly in front of the center of shaft 15 thus forming an offset knuckle joint. Therefore when the discs are forced over a serious obstruction the tendency of members 33 is to turn anti-clockwise against the pull of springs 71 (see Figure 4). It will be seen by scrutinizing Figure 3, that pivot bolt 50 is held in position by arms 35. Clearly since pivot bolt 36 is only slightly forward of the center of shaft 15, it will require but moderate size springs to hold the discs in their working position.

Slots 37 determine the extreme positions of tube 10 and it will be seen that when the discs have passed over the obstructions the springs will again force the discs to their original depth.

When it is desired to lock the discs against a yielding upward movement a bolt 72 (see Figure 6) is positioned in rear of members 35 and through the rear end of slots 37. The end of the slot through which bolt 72 extends is clearly shown in Figure 3. Thus when this bolt is used, the device will operate exactly the same as U. S. Patent No. 2,426,354 or in the design shown in Figure 7.

It will be seen that my improved stone jumping attachment may be conveniently installed on the disc tiller shown in U. S. Patent No. 2,426,354, that many parts shown in Figure 7 are interchangeable with parts used on the present invention and that when so installed, when desired the yielding means may be made inoperative; and that the device is simple, easily manufactured, easily understood and is efficient.

Clearly many minor detail changes may be made in the design shown without departing from the spirit and scope of my invention as recited in the appended claim.

Having thus shown and described my invention, I claim:

25 In an automatic release for a disc tiller, a main frame shaft with a carrying wheel mounted on its front end and two carrying wheels mounted on its rear end, a tube rotatably mounted on said frame shaft having rearwardly extending arms secured thereto and a disc gang rotatably mounted on the rear ends thereof, a half turn power clutch mounted on one of said carrying wheels and having an operating connection to said tube for raising and lowering said disc gang by turning the tube, said power lift operating connection to said tube comprising in combination, a forwardly extending arm secured to said tube, brackets rotatably mounted on said tube and on opposite sides of the forwardly extending arm, parallel and upwardly extending arms near the upper end of which is operatively connected said power lift clutch, the rear lower end of said parallel arms being pivoted to said brackets, the parallel arms being operatively connected to the forward end 40 of said forwardly extending arm, said brackets each having forwardly extending lever arms, springs operatively connecting the forward ends of the lever arms and said parallel arms near the upper end thereof, a stop associated with 45 said brackets and the lower end of said parallel arms to stop said brackets before said pivotal connection between said parallel arms and said brackets reaches dead center, whereby when said disc gang is forced to ride over a serious obstruction, said brackets will be caused to rotate and overcome the pull of said springs and cause said bracket to travel forwardly and permit said disc gangs to raise on the pivotal connection of said forwardly extending arm as an axis, and whereby after the discs pass over the obstruction, said springs will return the brackets and disc gang to their operating positions.

HOWARD M. JOHNSTON.
